CLAIM

2003/0413; E04C 2003/0439; E04C

The ornamental design for a support member for ceiling
system, as shown and described.

2003/046

DESCRIPTION

See application file for complete search history.

FIG. 1 is a perspective view of a support member for ceiling
system of the present design;(56) **References Cited**

FIG. 2 is a top view thereof;

U.S. PATENT DOCUMENTS

FIG. 3 is a bottom view thereof;

D223,235 S * 4/1972 Busby D25/132

FIG. 4 is a right side view thereof;

4,505,083 A * 3/1985 Mieyal E04B 9/122

FIG. 5 is a left side view thereof;

52/476

FIG. 6 is a rear view thereof; and,

4,520,609 A * 6/1985 Worley E04B 9/067

FIG. 7 is a front view thereof.

52/506.07

The evenly spaced broken lines depict portions of the
support member for ceiling system that form no part of the
claimed design.

4,554,718 A * 11/1985 Ollinger B23P 19/047

The dot dash broken lines represent a break in the article and
bounds of the claim that form no part of the claimed design.
